UNITED STATES PATENT OFFICE.

ISRAEL KINNEY, OF TORONTO, CANADA, ASSIGNOR OF ONE-HALF TO DETROIT SAW & TOOL WORKS, OF DETROIT, MICHIGAN, A CORPORATION OF MICHIGAN.

POCKET OR OTHER KNIFE.

SPECIFICATION forming part of Letters Patent No. 758,142, dated April 26, 1904.

Application filed June 20, 1903. Serial No. 162,392. (No model.)

To all whom it may concern:

Be it known that I, ISRAEL KINNEY, of the city of Toronto, in the county of York, Province of Ontario, Canada, have invented certain new and useful Improvements in Pocket or other Knives, of which the following is a specification.

My invention relates to certain improvements on a knife patented to me in the United States of America on June 24, 1902, under No. 702,968; and my object is to make the construction cheaper and better adapted to double-ended knives.

With this object in view my invention consists, essentially, in making the sides of the handle entirely separate or merely connected to such an extent as may be necessary to hold them in place, the spring-pressure being supplied by an independent bent spring engaging each side of the handle, substantially as hereinafter more specifically described and then definitely claimed.

Figure 1 is a perspective view of my improved knife, showing the back. Fig. 2 is an enlarged cross-section through *a a* in Fig. 1. Fig. 3 is an enlarged cross-section through *x y* in Fig. 1. Fig. 4 is a perspective view of a modification, showing the front of the knife. Fig. 5 is an enlarged section through *a a* in Fig. 4. Fig. 6 is a front plan view of Fig. 1 with the knife-blades open. Fig. 7 is a side elevation of the same with one blade open. Fig. 8 is a perspective view showing a modified form of the connection between the halves of the handle. Fig. 9 is a longitudinal section through the sides and blades of a knife provided with scale-pieces. Fig. 10 is a detail showing a countersunk rivet-head. Fig. 11 is a section through *a a* in Fig. 9. Fig. 12 is an elevation and section of a modification of the spring.

In the drawings like letters of reference indicate corresponding parts in the different views.

The handle of the knife is formed in halves *A A'*. These halves are preferably stamped out of metal, with a slight hollow or round, as shown particularly in Fig. 3. The exact

shape of this hollowing or rounding is not important provided a flange *a* be formed at the front edge of one half and a flange *b* at the back edge of the other half for engagement by the ends of a flat bent spring *C*, the function of which will be hereinafter more particularly described.

It will be noted on reference particularly to Fig. 6 that the sides of the handle are stamped out into a hollow convex form and that the ends are offset inwardly to contact with the butts of the blades. This not only affords the necessary room for the spring, but also gives the knife a suitably-rounded form to properly fill the hand when in use. The providing of sufficient room for the spring is probably the most important function filled by this particular shaping of the handle, and, if desired, the center only of the sides may be thus pressed out and the ends filled up to the same level by the use of suitable scale-pieces, as indicated in Fig. 9. In this view it will be seen that the projection in the sides of the handle is completely covered by the scale-pieces, giving the knife the outward appearance of an ordinary knife.

It will be noted that at the back the halves of the handle are flanged and that these flanges are in contact with one another, completely closing the gap between the halves.

Each end of the half *A*, it will be noticed, has flanges or projections *E* formed thereon to engage the butts of the knife-blades.

Each knife-blade is held in place by means of a rivet *F*, which passes through a hole formed in the side *A'* and a slot formed in the side *A*, substantially as in my prior patent previously referred to.

While I consider it preferable to have both flanges on one half of the handle, yet the flanges might be reversed at the opposite ends of the knife, this requiring, of course, a reversal of the positions of the slots and holes for the rivets at opposite ends of the knife. The ends of the rivets may be provided with rounded rivet heads or washers *c*, as shown in Figs. 1, 2, 6, and 7, or countersunk heads or washers may be employed, as shown in Fig. 10, in which

case the head or washer operating in the slot in the side A is of the dovetail form, as shown, to secure the necessary grip. This form is well adapted for use with the scale-pieces, such as shown in Fig. 9, as flush metal surfaces are thus obtained.

Instead of forming the flanges or projections E integral with the handle a separate pin E' might be employed, as shown in Fig. 8, or the construction illustrated in Figs. 4 and 5 may be adopted. By these views I show the flange or projection formed by a separate piece or yoke G, bent round the knife and clenched into a slight recess on one side of the knife. In this case the rivet F need not enter the side A at all, the bent piece G sufficiently holding the sides of the handle in position. When enlarged heads or washers are employed or when a separate piece or yoke is employed, they will preferably be made of such thickness as to extend out to the level of the sides of the body of the knife, as shown particularly in Figs. 4 and 6. (Note dotted lines.) If the projection or flange be formed as a pin, as shown in Fig. 8, the butt of the blade is preferably rounded, as indicated.

The spring C has its edges preferably serrated, as shown in Fig. 7, to better engage the sides of the handle. The spring operates substantially as shown in Fig. 7. When one blade is opened, the halves of the handle rock upon the rivet at the other end. The spring bends slightly as the knife-blade is opened up, maintaining at all times a spring-pressure on the halves, tending to press the flanges or projections E into contact with the butts of the blades.

While the spring G may be simply sprung in position, as shown, yet it may also, if desired, be riveted in place and its exact shape widely varied from that shown.

In a single-bladed knife the ends of the sides of the handle remote from the pivot-point of the blade must be connected in such a manner as to permit of a slight rocking action of the halves in the plane of the blade. A simple rivet may be employed; but I may also employ the detachable connection shown in Fig. 8, in which hooks H are formed on the two halves, which engage one another, the pressure of the spring tending to thus hold them in engagement.

A knife constructed in accordance with my improvement possesses numerous advantages over the form shown in my prior patent. As the spring is entirely separate from the halves of the handle, the handle need not be made of spring metal, but of something softer and cheaper. I further find that it is preferable to stamp out two independent halves than to stamp both halves integral out of the same plate.

It will be seen that with a double-bladed knife when a blade is opened the sides rock

from the opposite end, whereas with the integral spring-bridge shown in my prior patent the halves rocked on the central spring-bridge, and as this was necessarily quite close to the ends the spring was very stiff and awkward. With the separate spring the rocking of the halves occurs at the end, and the spring being separate can be made of fine quality clock-spring steel, possessing a superior resiliency to the integral spring-bridge.

If more spring is desired than is possessed by the arrangement shown in Figs. 3, 6, and 7, I may employ a long spring, bent, as shown in Fig. 12, in which the two ends engage the lip or flange a on one side of the handle and the center the lip or flange b on the other side.

It will be noted that the flange b extends entirely across the back of the knife, so that the spring lies substantially in a plane parallel to the sides. The spreading pressure of the form of spring shown in Fig. 3 is thus entirely done away with. To retain the spring in place, I cut shallow grooves in the flanges a and b, which, however, do not interfere with the free action of the spring.

What I claim as my invention is—

1. In a knife or similar article the combination of a handle comprising two metal sides having a rocking connection between them; a blade pivotally connected to one side remote from the said connection; a flange or projection carried by the other side for engagement by the butt of the blade; and a spring separate from the handle engaging each side of the handle to hold the flange in yielding engagement with the said butt, substantially as described.

2. In a knife or similar article the combination of a handle comprising two metal sides having a rocking connection between them at one end; a blade pivotally connected to one side remote from the said connection; a flange or projection carried by the other side for engagement by the butt of the blade; and a spring separate from the handle engaging each side of the handle to hold the flange in yielding engagement with the said butt, substantially as described.

3. In a knife or similar article the combination of a handle comprising two metal sides; two blades pivotally connected one to each end of one side; a flange or projection carried by the other side at each end for engagement by the butts of the blades; and a spring separate from the handle engaging each side of the handle to hold the flanges in yielding engagement with the said butts, substantially as described.

4. In a knife or similar article the combination of a blade; a handle comprising two metal sides, the end of one side being provided with a round hole, and the end of the other with a slot and a projection designed to engage the butt of the blade; a rivet extending through

the butt of the blade into the said hole and slot; a rocking connection between the other ends of the metal sides; and a spring separate from the handle engaging the sides intermediate the ends to hold the projection in yielding engagement with the said butt, substantially as described.

5. In a knife or similar article the combination of a handle comprising two metal sides having a rocking connection between them; a blade pivotally connected to one side remote from the said connection; a flange or projection carried by the other side for engagement by the butt of the blade; a curved flat spring arranged transversely in the space between the sides of the handle and suitably connected with the said sides to hold the flange in yielding engagement with the said butt, substantially as described.
10. 6. In a knife or similar article the combination of a handle comprising two metal sides having rocking connection between them; a blade pivotally connected to one side remote from the said connection; a flange or projection secured to and carried by the other side for engagement by the butt of the blade; and a spring separate from the handle engaging each side of the handle to hold the flange in

yielding engagement with the said butt, substantially as described.

7. In a knife or similar article the combination of a handle comprising two metal sides hollowed on the inside, one having an internal lip near the front edge, and the other near the back; a curved flat spring engaging the said lips; a rocking connection between the sides; a blade pivoted at the end of one side; and a flange on the other side engaging the butt of the blade, substantially as described.

8. In a knife or similar article the combination of a handle comprising two metal sides having a rocking connection between them; a blade pivotally connected to one side remote from the said connection; a yoke embracing the handle at one end and secured to the other side to form a flange for engagement by the butt of the blade; and a spring separate from the handle engaging each side of the handle to hold the flange in yielding engagement with the said butt, substantially as described.

Toronto, June 16, 1903.

ISRAEL KINNEY.
